CLAIM

The ornamental design for a fitting for racks for attaching sound effect devices, as shown.

DESCRIPTION

FIG. 1 is a perspective view of a fitting for racks for attaching sound effect devices, showing the new design;

FIG. 2 is a front view thereof;

FIG. 3 is a rear view thereof;

FIG. 4 is a top view thereof;

FIG. 5 is a bottom view thereof;

FIG. 6 is a left-side view thereof; and,

FIG. 7 is a right-side view thereof.
